(57) **CLAIM**

The ornamental design for a signage plate as shown and described.

DESCRIPTION

FIG. 1 is a perspective view of the first embodiment of a signage plate, shown in an environment of use;

FIG. 2 is a front view of the signage plate of FIG. 1;
FIG. 3 is a rear view of the signate plate of FIG. 1;
FIG. 4 is a left side view of the signage plate of FIG. 1;
FIG. 5 is a right side view of the signage plate of FIG. 1;
FIG. 6 is a top view of the signage plate of FIG. 1;
FIG. 7 is a bottom view of the signage plate of FIG. 1;
FIG. 8 is a perspective view the second embodiment of a signage plate, shown in an environment of use;
FIG. 9 is a front view of the signage plate of FIG. 8;
FIG. 10 is a rear view of the signate plate of FIG. 8;
FIG. 11 is a left side view of the signage plate of FIG. 8;
FIG. 12 is a right side view of the signage plate of FIG. 8;
FIG. 13 is a top view of the signage plate of FIG. 8;
FIG. 14 is a bottom view of the signage plate of FIG. 8;
FIG. 15 is a perspective view the third embodiment of a signage plate, shown in an environment of use;
FIG. 16 is a front view of the signage plate of FIG. 15;
FIG. 17 is a rear view of the signate plate of FIG. 15;
FIG. 18 is a left side view of the signage plate of FIG. 15;
FIG. 19 is a right side view of the signage plate of FIG. 15;
FIG. 20 is a top view of the signage plate of FIG. 15;
FIG. 21 is a bottom view of the signage plate of FIG. 15;
FIG. 22 is a perspective view the fourth embodiment of a signage plate, shown in an environment of use;
FIG. 23 is a front view of the signage plate of FIG. 22;
FIG. 24 is a rear view of the signate plate of FIG. 22;
FIG. 25 is a left side view of the signage plate of FIG. 22;
FIG. 26 is a right side view of the signage plate of FIG. 22;
FIG. 27 is a top view of the signage plate of FIG. 22;
FIG. 28 is a bottom view of the signage plate of FIG. 22;
FIG. 29 is a perspective view the fifth embodiment of a signage plate, shown in an environment of use;
FIG. 30 is a front view of the signage plate of FIG. 29;
FIG. 31 is a rear view of the signate plate of FIG. 29;
FIG. 32 is a left side view of the signage plate of FIG. 29;
FIG. 33 is a right side view of the signage plate of FIG. 29;
FIG. 34 is a top view of the signage plate of FIG. 29;
FIG. 35 is a bottom view of the signage plate of FIG. 29;
FIG. 36 is a perspective view the sixth embodiment of a signage plate, shown in an environment of use;
FIG. 37 is a front view of the signage plate of FIG. 36;
FIG. 38 is a rear view of the signate plate of FIG. 36;
FIG. 39 is a left side view of the signage plate of FIG. 36;
FIG. 40 is a right side view of the signage plate of FIG. 36;

(Continued)

FIG. 41 is a top view of the signage plate of FIG. 36; and, FIG. 42 is a bottom view of the signage plate of FIG. 36. The roof structure shown in broken lines in FIGS. 1, 8, 15, 22, 29 and 36 depict environmental structure that forms no part of the claimed design. The broken lines immediately adjacent the shaded areas represent the bounds of the claimed design while all other broken lines are directed to portions of the article and are for illustrative purposes only; the broken lines form no part of the claimed design.

1 Claim, 30 Drawing Sheets
